UNITED STATES PATENT OFFICE.

HEINRICH PANITSCHEK AND JOHANN AHORN, OF BÄRN, AUSTRIA-HUNGARY.

LOOM FOR THE MANUFACTURE OF KNOTTED CARPETS.

SPECIFICATION forming part of Letters Patent No. 716,092, dated December 16, 1902.

Application filed January 27, 1902. Serial No. 91,450. (No model.)

To all whom it may concern:

Be it known that we, HEINRICH PANITSCHEK and JOHANN AHORN, subjects of the Emperor of Austria-Hungary, residing at Bärn, in the Province of Moravia, in the Empire of Austria-Hungary, have invented certain new and useful Improvements in Looms for the Manufacture of Knotted Carpets; and we do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

This invention relates to a loom for manufacturing knotted carpets either with knots of the type characteristic of Persian carpets or with knots of that characteristic of Smyrna carpets by means of the same knotting apparatus without its being necessary to change any parts thereof should the loom be required for knotting carpets of one kind after having been used for making carpets of the other kind. In both a Persian knot and a Smyrna knot the piece of thread that forms the pile surrounds completely one of a pair of warp knot-threads, while, on the one hand, in the case of a Persian knot the piece of thread surrounds the other warp-thread only to the extent of one-half, (see Figure A of the accompanying drawings,) and in the case of a Smyrna knot, (Fig. B,) it surrounds this warp-thread also completely. A method of forming such pile fabrics is described in application, Serial No. 91,451, filed January 27, 1902. From this it will be seen that in making both a Persian knot and a Smyrna knot the ends of the piece of thread for the knot must be crossed around one of the two warp-threads. This crossing is effected by a pair of tongs, which consists of two slotted axially movable parts, of which one is inserted into the other and which are adapted to hold the piece of thread at two places, so that when one warp-thread is inserted into the loop formed between these parts by the piece of thread the ends of the thread are crossed around this warp-thread by rotating the pair of tongs through one hundred and eighty de-

grees. For the purpose of enabling knots of either kind to be formed by means of the same knotting apparatus, as desired, there is mounted on each of the pairs of knotting tongs, which are arranged parallel to one another, a sleeve which takes part in the rotary movement thereof, but is not axially movable, and is provided on its outer edge with two diametrically opposite hooks, which during the rotation of the sleeve grip the warp-thread first moved backward or "raised" and bend it into the form of an S, so that, as will be described in the following, by suitably fixing the initial position or the amount of the rotary movement to be imparted to the sleeve Persian or Smyrna knots can be formed, as desired.

Figs. 1 and 2 of the accompanying drawings show, respectively in elevation and in plan, essential parts of a weaving and knotting loom constructed according to this invention, several parts being shown in section and only three pairs of tongs being shown in Fig. 2. Fig. 3 shows in elevation and plan a device arranged on the upper part of the frame for enabling the warp-threads to yield in the direction of their length. Figs. 4 and 5 are respectively a top and a bottom plan of a complete pair of knotting-tongs. Fig. 6 shows in elevation means for opening the row of warp-threads. Fig. 7 shows working parts of the knotting and weaving loom in the positions occupied by them when the pairs of tongs are in their lowest position, but not in the initial position required for making one or the other kind of knots. Figs. 8 to 17, inclusive, show working parts of the weaving and knotting loom in the operation of making Persian knots. Figs. 18 to 26, inclusive, show working parts of the loom in the operation of making Smyrna knots. Fig. 27 shows two warp-threads and a finished Smyrna knot thereon.

Each pair of tongs for gripping a piece of thread to be knotted and for crossing its ends around one of the warp-threads comprises an outer cylindrical part 1 and a plunger 2, that can be slid axially therein. The two parts 1 and 2 are provided with straight axial slots 3 and 4. The cylinder 1 is provided near its free forward end with an open slot a, which

forms a hook *b*, that points backward. The forward end of the plunger 2 has an angular notch *c* for the purpose of gripping securely, in combination with the hook *b*, the piece of 5 thread which is inserted into the recess *a* in the manner to be hereinafter described and enabling the piece of thread to be properly held in the middle by the pair of tongs. The pairs of tongs are preferably carried in an inclined position, Fig. 1, by a support 5, which is mounted on a carriage 7, that can be moved up and down along a vertical controlling-shaft 6. The support 5 is moved to and fro across the looms by means of forked 10 guides *j* for the purpose of enabling the pairs of tongs to be moved after each knotting of a piece of thread by the distance apart of a pair of warp-threads. This horizontal movement of the pairs of tongs is effected step by 15 step by the controlling-shaft 6, whose step-by-step movement causes that of the support 5 by means of a chain 8. The step-by-step movement of the controlling-shaft 6 is produced by means of a ratchet device of known kind. The up-and-down motion of the support 5, and consequently that of the carriage 7, is effected by rods 9, that are connected by articulations with the support 5 and are operated in a known manner by means of 20 cams from the main shaft of the loom. In consequence of the articulations between the rods and the support the transverse motion of the latter is not interfered with, since the rods can swing transversely to the loom. 25

30 Each of the pairs of knotting-tongs is inserted into a tube 10, Fig. 1, which is rotatably mounted on the support 5 and is provided with a driving-key 11, which passes through the straight correspondingly wide and backwardly-directed slot 3 4 in the pair of tongs. On the tube 10 there is secured, by means of screws, a toothed wheel 12, which effects the rotation of the pair of tongs which is driven by the key 11 when the tube 10 is rotated. 35

40 The key prevents at the same time a movement of the cylinder 1 in relation to the plunger 2. The movement of the parts of the pairs of tongs in a longitudinal direction is effected by means of the following apparatus: On the support there is mounted a horizontal auxiliary shaft 13, on which on each side of the loom there are keyed two pairs of cams 15. These eccentrics, which are not shown in Fig. 1, but two pairs of which are 45 shown in Fig. 2, act on sliding rollers 16 of slotted levers 17, whose oscillatory motion by means of shafts 18 oscillates levers 19, that move, by means of links 20, sleeves 22, mounted on longitudinal rods 21, and also transverse rods 23, that are connected to the sleeves 22, thereby moving the parts of the pairs of tongs, the cylinders 1, and the plungers 2, which are adjustably secured in the transverse rods by means of nuts, in the direction 50 of their length. The cams 15 are so shaped that the movements of the pairs of tongs that are hereinafter referred to and are necessary

in the knotting operation (the closing and opening of the pairs of tongs and the simultaneous movement of the two parts of each 55 of the pairs of tongs when they are open or closed) are obtained. The arrangement of the slotted levers each with two bearing-rollers enables the time of the occurrence of these movements to be altered, as desired, by 60 adjusting the cams on the auxiliary shaft 13. The driving of the auxiliary shaft 13 is effected by bevel-wheels 24 from a vertical shaft 25, which is mounted in the support 5 and in which there is inserted a universal 65 joint 26, which enables the motion to be transmitted without interfering with the to-and-fro movement of the support. The shaft 25 is driven in a known manner from the main shaft. 70

75 The rotary movement of the pairs of tongs is effected by a common rack 14, which engages with all the toothed wheels 12 and the movement of which is likewise effected by the auxiliary shaft 13. For this purpose there is 80 mounted on the shaft 13 a cam 27, (shown only in Fig. 2,) which acts on a bearing-roller carried by an arc-shaped lever 28, that is adapted to oscillate about a shaft 18, which oscillates, by means of a chain 30 led around a 85 pulley 29, an arc-shaped lever 31, and through this lever, by means of a chain 32, the rack 14.

90 Each of the bands 33, containing the pieces of thread, consists of two parallel longitudinal threads, between which the pieces of thread to be knotted are held at certain distances apart, so that they can be easily drawn out. The succession of colors made by these pieces of thread corresponds to the pattern of the carpet to be produced. These bands are 95 guided downwardly approximately at right angles to the pairs of knotting-tongs along arms 34, that are pivoted to the frame of the machine, and each of the two warp-threads of each band 33 passes around a pulley *d* on a 100 weighted lever *e*, so that the bands are normally held stretched and the insertion into the notches *a* of the cylinder 1 of the pieces of thread intended for knotting is insured. The warp-threads after having been stripped 105 of the pieces of thread are guided by the pulleys *d* to a device for tightening and winding up the warp-threads. 110

115 The tightening of the bands is effected automatically by the weighted levers *e* after 120 each drawing out of a piece of thread, whereupon the levers *e* are raised by means of a bar *f*, which is arranged underneath them, is common to them, and can oscillate about the axis of a shaft *w*, so that the warp-threads which 125 have thus been made slack can be drawn tight and wound up by the said device. The shaft *w*, that carries the bar *f*, has attached to it an arm *v*, which is operated by the main shaft at certain times by means of a rod 40 (indicated in Figs. 1, 2, and 7 by dotted lines) and other known parts. 130

135 Each piece of thread that is to be knotted is placed on two slightly-springy forks *g g*,

Figs. 1, 2, and 7, arranged at a distance apart corresponding to the distance apart of the warp-threads and is supported thereby. The following piece of thread is held sufficiently 5 by two slightly-projecting pieces *h*, that are inclined toward each other and extend through the opening in the band between the two pieces of thread in question. These projections constitute a support for the band, so 10 that when the piece of thread to be knotted is drawn out the warp-threads are not drawn backward.

The two forks *g g* and the projections *h h* are mounted on a carrier *i*, Figs. 1 and 7, 15 which is attached to the under side of a bar *35*, Figs. 1, 2, and 6, which is carried by the arms *34* and can be slid in the direction of the width of the loom. Two bars *k*, Figs. 1, 2, and 6, are held against this bar *35* by means 20 of bolts *l*, which pass through longitudinal slots *m* in the bars *k*, so that the bars *k* can move to and fro in the direction of their length. The bars *k* carry at parts opposite to the pairs of knotting-tongs pairs of knife- 25 like sharpened pushers *n*, which when the arms *34* swing inward pass through the openings formed by the pairs of displaced or raised warp-threads. The bars *k* are slid in opposite directions after the pairs of pushers have 30 been inserted, so that the row of warp-threads is opened out by the pusher *n* at both sides of each pair of warp-threads inserted into a pair of knotting-tongs. The corresponding pair of knotting-tongs can be inserted into the 35 opening thus formed until the notch *a* of the cylinder of the pair of tongs comes under the piece of pattern-thread (*i. e.*, the piece of thread of the pattern-band) to be knotted. For the purpose of effecting the to-and-fro 40 movement of the pushers one of the two rods *k* is connected by means of a link *o*, Figs. 2 and 6, with a bell-crank lever *p*, which is oscillated periodically by means of a rod *q*, operated in a known manner, and consequently 45 moves the rod *k* longitudinally. The second bar *k* is connected to the other bar *k* by means of links and a two-armed lever *r*, Fig. 6, in such a way that the two bars will move in opposite directions, as required.

50 The movement of the arms *34* and the displacement of the bar *35* in the direction of its length is effected in a known manner from the main shaft of the loom.

The described arrangement enables to bring 55 the pieces of pattern-threads to be knotted immediately from the pattern-band into the knotting-tongs, whereby the feeding apparatus generally employed until now for the said purpose is dispensed with and, besides, the 60 knotting operation is effected in a perfectly sure and automatic manner.

In the following description that part of the weaving and knotting loom is described 65 which enables Persian or Smyrna knots to be formed by means of the same knotting apparatus without its being necessary to change

any portion of the same when it is desired to pass from one kind of knots to the other.

On the outer end of each of the tubes 10 through which the pairs of tongs 1 2 extend 70 there is placed a sleeve *36*, which is rigidly connected to this tube by the key *11*, so that it must rotate therewith, but cannot move axially. The sleeve *36* has at its end a thicker portion *39*, of which the inner edge forms a 75 single screw-thread. The outer free edge of the thicker portion is provided with two gripping-hooks *37* and *38*, which are opposite to each other and of which the hook *37*, located at the middle of the screw-thread, projects 80 farther (in the direction of the length of the sleeve) than the other hook *38*, which is at the outer end of the screw-thread. The openings in the hooks have inclined acting edges, which are indicated in Figs. 4 and 5 by dotted 85 lines. These inclined edges are parallel, but they act in opposite directions on the warp-thread gripped by the hooks when the sleeve is rotated, since the warp-thread is in front of the inclined edge of the hook *37*, but behind the inclined edge of the hook *38*, as will be seen from Figs. 4 and 5. If this sleeve is placed in such an initial position that the notch *a* in the corresponding pair of tongs faces upward after three-quarters of a revolution 90 of the sleeve and the pair of tongs, the pair of tongs can engage with the band for the purpose of drawing out a piece of thread, and thereby forming a Persian knot. On the other hand, if the initial position of the sleeve 95 is such that the notch *a* of the pair of tongs faces upward only after one and a quarter revolutions a Smyrna knot is formed. This will be hereinafter explained in detail, and the mode of operation of the weaving and 100 knotting loom in forming Persian and Smyrna knots will be described in detail with reference, respectively, to Figs. 8 to 17, inclusive, and to Figs. 18 to 27, inclusive.

I. *The formation of a Persian knot.*—First. 110 All the parts are in the positions shown in Fig. 7, the carriage 7 and the support 5 are in their lowest positions, and the pair of tongs in question is withdrawn into the sleeve. The pair of tongs and the sleeve are turned 115 backward through ninety degrees in the direction indicated by the arrow *z*, Fig. 7, so that the former comes into the position shown in Fig. 8. Second. The support, together with the pair of knotting-tongs, moves upward until the latter comes to rest about one centimeter below the piece of thread lying on the forks *g*. The first warp-thread is then raised, so that it bears against the edge of the sleeve, as shown in Fig. 9. (The second warp-thread indicated by dotted lines is not yet raised.) The pair of tongs is then turned forward and moves idly first through ninety degrees until the hooks *37* and *38* bend the first warp-thread in two places, as shown in Fig. 10. When the pair of tongs has been rotated through one hundred and eighty degrees, Fig. 120 125 130

10, the second warp-thread is raised and placed against the edge of the sleeve, so that after a further rotation of the pair of tongs through ninety degrees the first warp-thread 5 is bent to the form of an **S** and the second warp-thread is engaged by the hooks, but is still straight, as shown in Figs. 11 and 12. As one of the warp-threads must always be slackened in the direction of its length, so as to enable the **S**-shaped loop or twist to be formed, it is passed at the top over a rounded bar *u*, Fig. 3, which extends beyond the width of the fabric and is carried by arms *s* of a shaft *t* and partly around the latter. 15 The shaft *t* is connected by means of an arm with a rod *y*, which is released at a certain moment by an ordinary cam and is held by a weak spring *x*, so that the thread can be drawn forward to the extent necessary for 20 forming the before-mentioned twist. The pair of tongs has, therefore, after three-quarters of a revolution, as is necessary in this case, come into such a position that its notch *a* is at the top. Third. The pair of tongs is 25 now moved forward, so that the parts of the two warp-threads located between the hooks enter the slots 3 4 of the tongs. Thereupon the support is raised one centimeter, whereby the piece of pattern-thread to be knotted 30 is caused to enter the notch *a*, as shown in Fig. 13. The entire preliminary fabric is then moved somewhat outwardly by swinging the arms 34, so that the piece of thread to be knotted enters the curved portion or concavity of the hook *b*, as is indicated by dotted lines in Fig. 13. Fourth. The plunger 2 of the pair of tongs is moved forward a short distance, so that the pair of tongs is closed and the piece of thread is gripped in the middle 35 40 and held securely by the pair of tongs. Fifth. The pair of tongs then returns closed, so as to draw the piece of thread out of the pattern-band, Fig. 14. During the return of the tongs the plunger 2 moves somewhat outwardly, 45 Fig. 15, and then returns immediately, so that the piece of thread forms the loop required for the knot, as shown in Fig. 16. The pair of tongs now passes back through the before-mentioned opening in the row of warp-threads 50 55 until it arrives behind the latter. By rotating the sleeve slightly backward the second and later-raised warp-thread is released from the hook. If it is now let go, it enters, as required, into the still-open loop formed by the piece of thread. Sixth. The support, with the still-unfinished knot, then moves downward, and the pair of tongs, which in the meantime has been withdrawn behind the edge of the sleeve for the purpose of enabling 60 the crossing of the piece of pattern-thread around the second warp-thread and of the winding backward or uncoiling of the **S**-shaped loop formed by the first warp-thread, is rotated backward through one hundred 65 and eighty degrees, Fig. 17, just in front of the finished work, so that the ends of the piece of pattern-thread are crossed around

the second warp-thread and the before-mentioned **S** twist or coil of the first warp-thread is undone or taken out. Thereupon the pair 70 of tongs, including the plunger, is again moved forward to the row of warp-threads, and the Persian knot thus completed is drawn close down to the finished fabric. The pair of tongs is then again opened by the backward 75 movement of the plunger, whereby the finished knot is released. The pair of tongs 12 is now moved backward again and withdrawn into the sleeve, Fig. 7. Before the next knot is formed the pair of tongs and the sleeve 80 must be rotated backward through ninety degrees.

II. *The formation of a Smyrna knot.*—First. The pair of tongs and the sleeve are rotated forward through about ninety degrees 85 or backward through about two hundred and seventy degrees from the position shown in Fig. 7. Whereas formerly—*i. e.*, in forming the Persian knot—the hook 37 was on the right-hand side, Fig. 9, it is now located on 90 the left-hand side, as is indicated by dotted lines in Fig. 18. The pair of tongs is completely withdrawn, as in the previous case, so that its free forward end lies within the sleeve. After the support has been raised 95 in the manner hereinbefore described the first warp-thread is raised—*i. e.*, drawn back—and occupies a position at right angles to the axis of the pair of tongs in consequence of the inclined position of the latter. 100 The first warp-thread raised then bears against the unnotched edge of the thicker portion of the sleeve. Second. The sleeve is rotated through about ninety degrees forward—*i. e.*, in the direction indicated by the 105 arrow in Fig. 18—so that the two hooks grip the warp-thread. In this case the aforesaid acting inclined edges of the openings in the hook cause a slight bending of the warp-thread at two places in the direction of the 110 length of the pair of tongs, as will be seen from the side elevation included in Fig. 18, and the upper part of the warp-thread is moved forward or outward in relation to the lower part of the warp-thread. Third. The 115 sleeve moves farther in the direction indicated by the arrow. This causes the warp-thread to be bent, as shown in Fig. 19. During the further movement of the sleeve the lower portion of the warp-thread is compelled 120 to wind or coil upon the smooth portion of the sleeve by the thicker edge of the sleeve, which begins at the lower hook 38 or the opening therein and is wound in the form of a screw-thread, whereas the upper portion of 125 the warp-thread, which is moved somewhat forward by the inclined edge of the hook 37, can pass the front surface of the sleeve, as shown in Fig. 20. Fourth. The hook 37 has passed beyond its lowest position and the 130 other hook 38 beyond its highest position. The upper portion of the warp-thread has slid away from the hook 37, so as to form a closed loop around the other hook 38, as

shown in Fig. 21. Fifth. The sleeve rotates further and the hook 38 draws the upper portion of the warp-thread with it so far that it crosses the opening in the sleeve, and the empty hook 37 finally engages with this portion of the warp-thread again, Fig. 22. Simultaneously with this the movement of the sleeve is completed and the notch *a* in the pair of tongs has come to the top, as required, after one and one-fourth revolutions of the pair of tongs and the sleeve. The loop of the first warp-thread which is required for the formation of the Smyrna knot, but is not permanent, is now formed. Sixth. Thereupon the pair of tongs is moved forward, so that the warp-thread which crosses the opening in the sleeve enters the slot in the pair of tongs. At the same time the second warp-thread is raised and also enters the slot in the tongs, Fig. 23. Seventh. Thereupon the same operations occur as in the case of the formation of a Persian knot—namely, the opening of the row of warp-threads, the passing of the pair of tongs through the opening, the gripping and drawing out of the piece of pattern-thread, the formation of the loop of the piece of thread, and the releasing of the second warp-thread, which enters the open loop of the piece of pattern-thread, Fig. 24. Eighth. The pair of tongs is drawn back until its free end, which contains the piece of thread, is behind the edge of the sleeve. Ninth. Thereupon the pair of tongs, and consequently the sleeves, is rotated backward through one hundred and eighty degrees, so that the ends of the piece of pattern-thread are crossed and the temporary loop of the warp-thread surrounds only one part of the pair of tongs, Fig. 25. Tenth. By rotating the sleeve through somewhat more than the said one hundred and eighty degrees, the pair of tongs being simultaneously pushed forward to the row of warp-threads, the loop of the warp-thread falls from the sleeve, and thus reaches one of the crossed ends of the piece of pattern-thread, Fig. 26, whereupon the pair of tongs is again rotated backward somewhat more than one hundred and eighty degrees, so that the finished knot can be pushed into the proper position on the finished fabric. Eleventh. By the tension in the warp the loop of the warp-thread is undone, and a like loop is consequently formed in the corresponding end of the piece of pattern-thread, Fig. 27, completing the Smyrna knot, which can be pushed down to the fabric, whereupon by opening the pair of tongs the finished knot can be released. Twelfth. The support with the pair of tongs moves upward and is then moved transversely by the distance apart of two warp-threads or of a pair of warp-threads. Now in order to form a new Smyrna knot the pair of tongs must, as hereinbefore stated, be brought into the initial position required therefor.

By comparing Figs. 11 and 22 it will be seen

that in producing a Smyrna knot a somewhat longer piece of one warp-thread is wound on the periphery of the sleeve than in the case of a Persian knot, so that the latter requires less slackening of the warp-thread. The aforesaid cam for the slackening or letting-off device, which is driven from the main shaft, releases the rod *y*, Fig. 3, at the proper moment; but the rod is held by the spring *x* in such a way that the warp-thread does not become slack. During the succeeding rotation of the pair of tongs and the sleeve—*i. e.*, when the warp-thread is wound on the sleeve—the spring *x* yields to the pull of the warp-thread by an amount equal to the amount of warp-thread wound upon the sleeve, whether a Persian or a Smyrna knot is being made.

When the weaving and knotting loom has to be adjusted for making knots of another kind—for example, Persian knots after being used for making Smyrna knots—the cam 27, which effects the rotation of the pairs of tongs and the sleeves and moves the rack 14, is adjusted only so as to change its acting cam-surface. The construction of such an adjustable cam is known.

We claim—

1. In a loom, in combination with warp mechanism and means for positioning and feeding strips of pattern fabric cut in the direction of its warp; of knotting mechanism,

means to move said mechanism to the warp-threads to engage pairs of them and to and from the pattern fabric to seize short weft-threads thereof, and means to actuate the knotting mechanism, whereby said short threads will be knotted around respective warp-threads.

2. In a loom, in combination with warp mechanism and means for positioning and feeding a pattern fabric cut in the direction of its warp into strips; of knotting mechanism, means to move said mechanism to the warp-threads to engage pairs of them and to and from the strips of pattern fabric, means to actuate the knotting mechanism, whereby said short threads will be knotted around pairs of warp-threads and a change device to cause the knotting mechanism to knot either a Persian or a Smyrna knot, substantially as described.

3. In a loom, knotting mechanism comprising a sleeve having warp-engaging hooks thereon, a cylinder therein having forked ends, a plunger in the cylinder also having forked ends, and means to simultaneously rotate the parts, and devices to reciprocate the plunger and cylinder within the sleeve, substantially as described.

4. In a loom, knotting mechanism comprising a sleeve having warp-engaging hooks thereon and means to rotate said sleeve, a cylinder having forked ends in said sleeve, a plunger also having forked ends in the cylinder, both cylinder and plunger independently movable axially, and a key passing through

the sleeve and the forks of said cylinder and plunger, whereby said parts are simultaneously rotated, substantially as described.

5. In a loom, knotting mechanism comprising a sleeve having warp-engaging hooks on its end and means to rotate the sleeve, a cylinder having forked ends, and pile-thread-engaging hooks thereon and axially movable in the cylinder, and a key passing through the sleeve and forks of said plunger and cylinder, whereby the parts are simultaneously rotated, substantially as described.

6. In a loom, knotting mechanism comprising a sleeve, two oppositely-situated warp-engaging hooks and a single screw-thread on its end, said hooks of different form, a cylinder having a forked end in the sleeve and pile-thread-engaging hooks on the forks, a forked plunger in the cylinder having pile-thread-holding notches in its end, and a key passing through the sleeve and the forked end of the cylinder and plunger, to simultaneously rotate the parts, and means to independently move the cylinder and plunger axially, substantially as described.

7. In a loom, in combination with warp mechanism and means to position and feed strips of pattern fabric; of knotting mechanism, means to shed pairs of warp-threads to the knotting mechanism and means inserted into the warp at the points where pairs of warp-threads have been shed to laterally open the warp, mechanism to move the knotting mechanism through the opened warp to engage short weft-threads of the pattern fabric to withdraw them therefrom and knot them to the warp-threads engaged by the knotting mechanism, substantially as described.

8. In a loom, in combination with warp mechanism and means to position and feed strips of pattern fabric, and means to shed pairs of warp-threads; of sleeves having warp-engaging hooks on their ends and a coöperating forked cylinder and forked plunger in each sleeve, means to slacken warp-threads engaged by the hooks to wind them upon said sleeves on one side of the warp, pushers opposite each sleeve and a coöperating cylinder and plunger, on the other side of the warp to enter the spaces left by the shed warp-threads to laterally open the warp, mechanism to move the cylinders and plungers through the opened warp to seize short weft-threads from the strips of pattern fabric to knot them around shed warp-threads, substantially as described.

9. In a loom, the combination with knotting-forks and warp mechanism; of means to carry and feed strips of a pattern fabric, and means to successively move them across the warp behind successive pairs of warp-threads, forks to embrace warp-threads of the pattern fabric and means to prevent the drawing of said warp-threads during the removal of a short weft-thread, and tension-rollers for said pattern fabric, warp-threads and means to

periodically release the tension thereon, substantially as described.

10. In a loom, the combination with knotting-forks and warp mechanism; of means to carry and downwardly feed strips of a pattern fabric, and means to successively move them across the warp behind successive pairs of warp-threads, spring-forks to embrace warp-threads of the strips of pattern fabric below the point of withdrawal of the short weft-threads therefrom, and projections *h* above said spring-forks to take between warp-threads of the pattern fabric to prevent their drawing during the removal of the short weft-threads therefrom, tension-rollers for the pattern-fabric warp-threads, weighted levers in which the rollers are journaled and a bar *f* to simultaneously and periodically lift the levers to remove tension on the pattern-fabric warp-threads, substantially as described.

11. In a loom, knotting mechanism comprising a sleeve having warp-engaging hooks on its end, a cylinder therein having forked ends and pile-thread-engaging hooks thereon, a forked plunger in the cylinder, means to connect said parts to permit their independent reciprocation and simultaneous rotation, a pinion on the sleeve, cam-operated levers to independently reciprocate the cylinder and plunger within the sleeve, a rack engaging the pinion and a change device to reciprocate the rack to rotate the knotting mechanism, whereby either a Persian or a Smyrna knot may be made, substantially as described.

12. In a loom, a carriage, knotting mechanism thereon comprising sleeves having warp-engaging hooks thereon, hook-ended, forked cylinders therein and forked plungers in the cylinders, a bar connecting all the cylinders and one connecting all the plungers, cam-operated mechanism to reciprocate the bars to actuate the cylinders and plungers, and means to move the carriage transversely of the loom to operate on successive pairs of warp-threads, substantially as described.

13. In a loom, a carriage, knotting mechanism thereon to seize and knot properly-fed pile-threads around pairs of warp-threads, a driven auxiliary shaft and a second shaft on the carriage, cams on said auxiliary shaft and coöperating levers on the second shaft, said levers operating knotting mechanism, all vertically, laterally and transversely movable with the carriage, substantially as described.

14. In a loom, a carriage, knotting mechanism thereon comprising sleeves having warp-engaging hooks thereon, a hook-ended, forked cylinder in each sleeve, a forked plunger in each cylinder, a pinion to revolve each sleeve and means to cause the simultaneous rotation of the coöperating cylinder and plunger, and a rack to simultaneously rotate all the sleeves; a driven auxiliary shaft and a second shaft on the carriage, cams on the auxiliary shaft and coöperating levers on the

second shaft, one of said levers adapted to communicate motion to a change-arc to operate the means to rotate the knotting mechanism and the others to impart reciprocating motion to the cylinders and plungers, substantially as described.

15. In a loom, a carriage, knotting mechanism thereon comprising sleeves having warp-engaging hooks thereon, a hook-ended, forked cylinder in each sleeve, a forked plunger in each cylinder, a pinion to revolve each sleeve, a key through the sleeve and parts therein, and a rack to simultaneously rotate all the sleeves and their contained parts; a driven auxiliary shaft and a second shaft on the carriage, a cam on the auxiliary shaft, a

lever on the second shaft, a change-arc on the carriage, chain-connected to the lever and to the rack, slides on the carriage, levers on the second shaft to actuate said levers and 20 bars on the slides, one to reciprocate all the cylinders and the other all the plungers, substantially as described.

In testimony that we claim the foregoing as our invention we have signed our names in 25 presence of two subscribing witnesses.
